UNITED STATES PATENT OFFICE.

JOSIAH E. NIGHTINGALE, OF DANVERS, MASSACHUSETTS.

MUSIC-LEAF TURNER.

SPECIFICATION forming part of Letters Patent No. 411,052, dated September 17, 1889.

Application filed March 25, 1889. Serial No. 304,630. (No model.)

To all whom it may concern:

Be it known that I, JOSIAH E. NIGHTINGALE, a citizen of the United States, and a resident of Danvers, in the county of Essex and State of Massachusetts, have invented new and useful Improvements in Music-Leaf Turners, of which the following, taken in connection with the accompanying drawings, is a specification.

This invention relates to improvements in music-leaf turners, and it is carried out as follows, reference being had to the accompanying drawings, wherein—

Figure 1 represents a front perspective view of the device. Fig. 2 represents a rear perspective view of the spring-pressed clamping-jaws for holding the back edge of the sheet-music in place. Fig. 3 represents a partial section on the line *z* shown in Fig. 1. Fig. 4 represents an enlarged cross-section of the holding and releasing device for successively releasing the sheets whenever required, and Fig. 5 represents a modification of said holding and releasing device.

Similar letters refer to similar parts wherever they occur on the different parts of the drawings.

a represents the foot or base adapted to be supported on the lower ledge or shelf of a music-stand or other convenient music-support, which foot or base is preferably made of metal and covered on its under side with cloth, felt, or other soft material, as may be desired. To said base-part *a* is hinged, by means of a detachable pin *b'*, the clamp-bar *b*, on the under side of which is secured in a suitable manner the rod or wire *b''*, to which are pivoted the clamping-jaws *c c*, between which the back edge of the sheet-music is confined while in use. The said clamping-jaws are automatically forced toward each other by the influence of the spring *c'*, having its ends pressing against the back of the respective clamping-jaws *c c*, as shown in Fig. 2.

c'' c'' are ears or projections on the clamping-jaws *c c*, for the purpose of expanding said jaws against the influence of the spring *c'* while placing the sheet-music between or removing it from said clamping-jaws.

To the lower portion of the clamp-bar *b* is secured in a detachable manner, preferably by means of a thumb-nut or screw *d*, the cross-bar *E*, having about midway upon it

suitable ears or projections for the support of the pin *e*, on which the leaf-turners are loosely pivoted, as shown.

In practice I prefer to use about ten of such leaf-turners, each consisting of a perforated hub *f*, located on the pin *e*, and provided with a radial wire arm *F*, having its free end *F'* bent upward and adapted to receive the lower edge of one of the leaves of the sheet-music. When released, the leaf-turners are automatically swung toward the left by the influence of the coiled springs *f'*, secured in one of their ends to the left-hand portion of the bar *E* and in their other ends to the respective hubs *f f*, or suitable projections thereon, and when so released the wire arms *F* are guided into and made to rest in a slotted or forked bracket *E'*, forming a part of or secured to the bar *E*, as shown in Fig. 1.

The right-hand end of the bar *E* is provided with a locking and releasing device for the spring-actuated leaf-turner, which is constructed as follows: It consists of a forked bracket *E''*, having a slit *E³* adapted to receive the wire arms *F* of the leaf-turners, as shown. In the bracket or bearing *E''* is pivoted at *e'* the finger-lever *G*, having an upwardly-projecting arm *g*, terminating in its upper end as a rearwardly-projecting lip *g'*, against which the uppermost of the spring-pressed wires *F* is held before being released, as shown in Fig. 4. In addition to the lip or stop projection *g'*, the lever *G* has a rear portion *g''*, terminating in its upper end as a forwardly-projecting wedge or incline *g³*, as shown in Figs. 4 and 5, which, when the lever *G* is depressed, is caused to pass by the slit *E³*, and thus preventing more than one of the leaf-turners from being released at a time. The lever *G* is automatically held in the locked position shown in Figs. 4 and 5 by the influence of the spring *h*.

In the modification shown in Fig. 5 the part *g g'* is made separate from the lever *G* and pivoted to it at *g⁴*, its lower end being actuated by the spring *h* and forced against a side projection *g⁵* on the lever *G*, the operation of this device being, however, substantially like the solid lever shown in Fig. 4.

In using the invention the plate *a* is supported on the ledge of a music-rack, or any other suitable object, with the bar *b* resting

against the music-rack or musical instrument—such as, for instance, pianos or organs. The back edge of the sheet-music is then inserted between the spring-pressed clamping-jaws *c c* and the lower edges of the music-sheets attached to the respective wire loops or holders *F'*, after which the wire arms *F* are swung toward the right until they are all locked and confined in the slotted bracket *E''*;

10 or the said wire arms may first be placed in said slotted brackets *E''*, and the music-sheets afterward attached to the wire loops or holders *F'*, this being optional with the player. If it is desired to turn over a leaf, all the

15 player has to do is to push with one of his fingers on the lever *G*, as shown in Fig. 1, causing said lever to be tripped sufficiently to allow the lip *g'* to pass by the slit *E³*, when the uppermost of the wire arms *F* is liberated and

20 caused to swing half a revolution toward the left by the influence of its spring *f'*, and in so doing turning over the sheet attached to it. By reason of the wedge or inclined projection *g³* passing by the slit *E³*, the next

25 leaf-turner in the series is prevented from escaping until the lever *G* is released and again depressed, and so on until all the desired sheets are turned over.

When not in use, the device can be taken apart and packed in a very small and convenient shape, simply by removing the pin *b'* and the nut or screw *d*, thus allowing the plate *a* and bars *E* and *b* to be laid parallel with each other, as may be desired.

Having thus fully described the nature, construction, and operation of my invention, I wish to secure by Letters Patent, and claim—

The leaf-turner as described, consisting of a plate *a* and bar *b*, hinged to it, and the bar *E*, detachably secured to said bar *b*, said bar *E* having pivoted to it a series of spring-pressed leaf-turners *F F'*, and the said bar *b* having hinged to it the spring-pressed clamping-jaws *c c*, as described, and a locking and releasing device for the leaf-turners, substantially as and for the purpose set forth.

In testimony whereof I have signed my name to this specification, in the presence of two subscribing witnesses, on this 16th day of March, A. D. 1889.

JOSIAH E. NIGHTINGALE.
